REAR VIEW MIRROR ASSEMBLY FOR ATTACHMENT TO EYEGLASS FRAME

Harry J. Beethoven, P.O. Box 1829,
West Palm Beach, Fla. 33402

Filed June 3, 1974, Ser. No. 475,795

Term of patent 14 years

Int. Cl. D12—16
U.S. Cl. D12—187

FIG. 1

FIG. 2

FIG. 3

FIG. 4

FIG. 5

FIG. 6

FIG. 1 is a top plan view of a rear view mirror assembly for attachment to eyeglass frame showing my new design;

FIG. 2 is a left side elevational view thereof;

FIG. 3 is a right side elevational view thereof;

FIG. 4 is a front elevational view thereof;

FIG. 5 is a rear elevational view thereof; and

FIG. 6 is a bottom plan view thereof.

I claim:

The ornamental design for a rear view mirror assembly for attachment to eyeglass frame, substantially as shown.
